FIG. 1

FIG. 2

FIG. 3

FIG. 4

FIG. 5

FIG. 6

FIG. 7

FIG. 1 is a top plan view of an egg tray showing my new design;

FIG. 2 is a view in end elevation taken from the lower edge of FIG. 1;

FIG. 3 is a view in vertical section taken along line 3—3 of FIG. 1 and looking in the direction of the arrows;

FIG. 4 is a side elevational view thereof taken from the right of FIG. 1;

FIG. 5 is a fragmentary and enlarged sectional view taken along line 5—5 of FIG. 1 and looking in the direction of the arrows;

FIG. 6 is a fragmentary and enlarged sectional view taken along line 6—6 of FIG. 1 and looking in the direction of the arrows; and

FIG. 7 is a fragmentary perspective view taken from the lower left side of FIG. 1.

It is understood that the remainder of the tray has the same appearance as the lower right-hand corner as shaded in FIG. 1.

I claim:

The ornamental design for an egg tray, as shown and described.
